(57) **CLAIM**

The ornamental design for the circular double barbed plate with fastener, as shown and described.

DESCRIPTION

FIG. 1 is a perspective view of the circular double barbed plate with fastener of the present design;

FIG. 2 is a side elevational view of the design, all other sides being identical thereto;

FIG. 3 is a top plan view thereof; and,

FIG. 4 is a bottom perspective view thereof.

The broken lines shown on the drawings are for illustrative purposes only and form no part of the claimed design.
